CLOCK CABINETS

Virgil C. Welch, 4943 Huntington, Lincoln, Nebr. 68504

Filed Aug. 8, 1969, Ser. No. 18,593

Term of patent 7 years

Int. Cl. D10—01

U.S. Cl. D42—7

The figure is a perspective view of a clock cabinet showing my new design, the rear of the cabinet being substantially plain and unornamented.

I claim:

The ornamental design for clock cabinets, as shown.
